UNITED STATES PATENT OFFICE

LESTER L. LADD, OF LOCKPORT, ILLINOIS

KILN

Application filed September 28, 1931. Serial No. 565,502.

This invention relates to tunnel kilns used in firing ceramic ware.

Tunnel kilns may be classified as open firing kilns or muffle kilns. In the open type of kiln, the combustion gases are discharged directly into the ware passage. In the muffle type of kiln, a refractory muffle wall separates the ware passage from the combustion chamber to prevent the flames and gases of incomplete combustion such as carbon monoxide from reaching the ware.

The open type of kiln is very efficient but those heretofore in use have not been adapted for firing certain kinds of ware, such as glost ware, because the flames and carbon monoxide came into direct contact with the ware and discolored the glazed coatings.

The muffle type of kiln is not so efficient as an open kiln, but it is safer and more satisfactory for some purposes because the muffle prevents the flames and combustion gases from injuring the ware.

The main objects of this invention are to provide a tunnel kiln of the open type which approaches the safety of a muffle kiln; to provide improved means for withdrawing carbon monoxide from the combustion chamber and the ware passage; to provide an improved form of baffle which will prevent the flames from striking the ware but which will permit communication between the combustion chamber and the ware passage; to provide a baffle of this kind which will permit the roof of the tunnel to move freely when expanding and contracting under temperature changes; and to provide a construction of this kind which is adapted for use in connection with tunnel kilns of the straight or circular type.

An illustrative embodiment of this invention is shown in the accompanying drawings wherein:

Figure 1 is a top plan of a circular tunnel kiln, to which this invention is applied.

Figure 2 is an enlarged transverse vertical section of the kiln at the firing zone.

Fig. 3 is a horizontal section, taken on the line 3-3 of Fig. 2.

Fig. 4 is a fragmentary side elevation of one of the baffle walls.

In the form shown, the kiln is of the circular type comprising an annular conveyer 1 movable through an open loading and unloading zone 2, and through an arcuate tunnel 3 having a preheating zone 4, firing zone 5 and cooling zone 6.

The conveyer may be of the type shown in my co-pending application Serial 366,959 filed May 29, 1929 which has become Patent 1,842,411. It comprises an annular platform 7, provided with the usual aprons 8, and supported on an annular I-beam 9, to which is attached a mono-rail 10, which rides on a plurality of supporting wheels 10.1. Certain of the supporting wheels are motor driven for driving the conveyer.

The tunnel is supported on a fabricated metal frame structure comprising vertically disposed angle bars 11 and 12, which are connected to horizontal bars 13 and 14. The upper ends of the bars 11 are secured against spreading by horizontal tie rods 15, which are disposed above the tunnel. Supported on the frame bars 14, are concrete floor slabs 16 disposed on respectively opposite sides of the conveyer. Formed at the inner edges of these floor slabs, are troughs 17, which are filled with sand or other suitable sealing material adapted to coact with the aprons 8 to prevent the heat in the ware passage from reaching the bearings of the conveyer. Metal shields 18 form the inner walls of the troughs 17.

In the form shown, the tunnel 3 comprises a floor 19, side wall 20, and a roof 21, which define the preheating zone 4, firing zone 5 and cooling zone 6. Inasmuch as this invention relates primarily to the tunnel construction within the firing zone, the other zones have not been shown in detail.

The tunnel varies in cross section at different zones of the kiln. Extending through the tunnel is a central ware passage 22 through which the ware travels in the direction of the arrow shown in Fig. 1. My copending application Serial No. 565,501, filed September 28, 1931, shows a tunnel ventilating system which is well adapted for use in connection with a kiln to which this invention is applied.

The floor, walls, and roof of the kiln may

be made of various heat resisting materials such as brick, fire brick, tile, refractory, infusorial earth, and similar materials.

In the firing zone, the tunnel is formed to provide a pair of combustion chambers 23 located on respectively opposite sides of the ware passage 22. Fuel is delivered to these combustion chambers through nozzles 24 which extend into openings 25 in the side walls 20. The nozzles 24 are connected to manifolds 26 of a fuel supply system.

Located on respectively opposite sides of the ware passage in the firing zone, is a pair of baffles, each of which includes a pair of vertically disposed walls 27 and 28, which are mounted on the tunnel floor 19 and which are spaced from each other. Formed in these walls, are openings 29 to provide communication between the lower portions of the combustion chambers 23 and the ware passage 22. The openings 29 of the walls 27 are staggered with respect to those of the walls 28, so as to prevent the flames from entering the ware passage.

The inner walls 27 have outwardly projecting ledges 30 which rest upon the upper ends of the walls 28. As shown in Figure 2, the upper ends of the baffle walls are disjoined from the tunnel roof, so as to permit the roof to freely expand and contract under temperature changes. In order to prevent communication between the upper ends of the combustion chambers 23 and the ware passage, the baffle walls 27 are imperforate above the ledges 30, and the tunnel roof is provided with inclined aprons or shields 31 which engage the outer faces of the walls 27. These aprons 31 form, in effect, movable sections of the baffle walls 27. They permit the tunnel roof to expand and contract but they prevent any of the combustion gases in the upper portions of the chambers 23 from passing into the ware passage.

Carbon monoxide, which is the most injurious of all the gases of incomplete combustion, is very light and usually floats to the upper portions of the combustion chambers and ware passage. In order to skim off this injurious gas, to prevent damage to the ware, the tunnel roof is provided with a plurality of outlet pipes 32 leading to a manifold 33 connected to an exhaust fan 34.

In the form shown, the tunnel is provided with grooves 35 in the roof and floor of the firing zone so as to permit the insertion of an imperforate baffle 36 if one is desired.

In operation, the ware is loaded on the conveyer 1 in the zone 2 and it is moved successively through the preheating zone, firing zone and cooling zone of the kiln.

In the combustion chambers, the flames from the nozzles 24 strike against the baffle walls 27 and 28 and are thereby prevented from damaging the ware within the passage 22. Most of the carbon monoxide within the

combustion chambers rises to the top where it is trapped by the walls 27, aprons 31, and ledges 30. Some of the carbon monoxide may escape through the openings 29 but it would then rise to the upper part of the ware passage.

The exhaust fan 34 operates continuously and the lighter gases, including the carbon monoxide, are thereby withdrawn from the combustion chambers and the ware passage. With this improved construction, the ware passage is substantially free from any gases of incomplete combustion which would injure the ware.

Although but one specific embodiment of this invention has been herein shown and described, it will be understood that certain details of the construction shown may be altered or omitted without departing from the spirit of the invention as defined by the following claims:

I claim:

1. A kiln comprising a tunnel having a ware passage and a contiguous combustion chamber communicating with each other at their lower ends, a substantially imperforate baffle separating the upper portions of said ware passage and combustion chamber from each other, and means at the upper end of said combustion chamber for withdrawing the lighter combustion gases.

2. A kiln comprising a tunnel having a ware passage and a contiguous combustion chamber, a vertical baffle arranged between said ware passage and combustion chamber, the upper portion of said baffle being substantially impervious to gases, the lower portion of said baffle being perforate to permit certain of the combustion gases to enter said ware passage, and means for withdrawing the lighter gases from the upper portion of said chamber.

3. A kiln comprising a tunnel having a ware passage and a contiguous combustion chamber, and a pair of vertical baffle walls arranged between said passage and chamber and spaced from each other, said baffle walls having staggered openings forming tortuous passages providing communication between said chamber and ware passage.

4. A kiln comprising a tunnel having side walls and a roof defining a ware passage and a contiguous combustion chamber, a vertical baffle mounted on the floor of said tunnel and being perforated to permit communication between said chamber and passage, the upper end of said baffle being disjoined from said roof to permit said roof to freely expand and contract, and an imperforate skirt depending from said roof and slidably engaging one side of said baffle so as to form a movable section thereof.

LESTER L. LADD.
